UNITED STATES PATENT OFFICE.

CALVIN L. JOY, OF LOWELL, MASSACHUSETTS, ASSIGNOR TO DRAPER COMPANY, OF HOPE-DALE, MASSACHUSETTS, A CORPORATION OF MAINE.

LOOM-TEMPLE.

No. 882,827.

Specification of Letters Patent. Patented March 24, 1908.

Application filed October 7, 1907. Serial No. 396,128.

To all whom it may concern:

Be it known that I, CALVIN L. JOY, a citizen of the United States, and resident of Lowell, county of Middlesex, State of Massachusetts, have invented an Improvement in Loom-Temples, of which the following description, in connection with the accompanying drawings, is a specification, like letters on the drawing representing like parts.

10 This invention relates to loom-temples and it has for its object the production of simple and efficient means to prevent tipping of the temple head and its slide-bar due to wear of either the bar or the temple-stand, and also 15 to practically reduce such wear to a minimum.

To those skilled in the art it is well known that the inward pull of the cloth is exerted upon the roll in such manner that the tendency is to not only draw the rear end of the slide-bar inward against the adjacent portion of the temple-stand but also to tip or turn the slide-bar itself within the stand. As a result 25 the wear of the parts is rapid and the slide-bar is turned upon its longitudinal axis so that the temple-head and roll are tipped at an angle to the plane of the cloth, the inner end of the roll being highest, and interfering with the proper operation of the temple to 30 such an extent that such worn temples are discarded and new ones substituted.

By my present invention I am enabled to prevent such tipping or turning of the slide-bar and temple-head, and the life of the temple 35 as a whole is greatly prolonged.

The novel features of my invention will be fully described in the subjoined specification and particularly pointed out in the following claims.

40 Figure 1 is an inner side elevation of a loom-temple with one embodiment of my invention shown in connection therewith; Fig. 2 is a top plan view of the device illustrated in Fig. 1.

45 Referring to the drawings the temple-stand 1 having the longitudinally-slotted, lateral flange 2 by which the stand is held in position on the loom, the shank or slide-bar 3 longitudinally movable in the stand and provided at its rear end with the head comprising the cap 4, pod 5, and cloth-engaging roll 6, Fig. 1, and the depending heel 7, may be 50 and are of well known or usual construction in loom-temples.

55 The rear portion of the slide-bar 3 is made

rectangular in cross-section, as is common, to slide in the correspondingly shaped guiding portion of the stand, as usual.

The lateral pull of the cloth upon the roll 6 tends to pull the rear end of the slide-bar 3 inward toward the center of the loom, and also to turn or twist the bar, lifting the inner end of the temple-head, as has been pointed out, and I will now describe the means whereby such tendencies are obviated by my present invention.

Upon a suitable portion of the temple-stand, as for instance the rear end of the flange 2 I insert a fulcrum-stud 8, shown as a screw-stud, inserted in a threaded hole 9, see 70 dotted lines Fig. 1, and upon the stud I fulcrum a laterally-swinging or movable arm 10, having its shorter outer end upturned at 11 and threaded to receive an adjusting screw 12. The inner end of said screw bears 75 against the adjacent wall of the stand 1, as shown clearly in Fig. 2, so that by turning the screw in or out the angular position of the arm 10 will be changed.

The rear end of the arm is thickened and 80 preferably tapered somewhat, to form a toe 13, which enters loosely a socket or recess formed by parallel ears 14 formed upon the outer face of a guide-shoe 15, having a flat, extended face 16 adapted to contact with the 85 inner side of the slide-bar 3 adjacent the rear end of the temple-stand, as shown, the outer end of the shoe abutting against the adjacent inner end of the temple-stand.

By reference to Fig. 1 it will be seen that 90 the shoe is elongated to form a bearing surface for the slide-bar extended well beyond the stand, and it is broad enough to extend from the lower edge of the bar to above the longitudinal center thereof. The extended 95 wearing or bearing surface thus provided acts upon the slide-bar in the best position to prevent twisting or turning, viz:—from its lower edge upward, and at the rear end of the stand, to resist the inward pull of the 100 cloth toward the center of the loom.

There is a loose or slightly pivotal connection between the shoe and the supporting arm 10, as will be manifest, so that no matter 105 how the angularity of the arm may be varied by adjustment thereof the shoe will always remain with its wear or bearing face 16 in contact with and parallel to the side of the slide-bar. Were this parallelism not preserved there would be uneven wear between 110

the bar and the shoe, or between the bar and the stand, or both, and the object of the invention would be defeated.

The arm 10 supports the shoe vertically and prevents movement thereof toward the temple-head, as the toe engages the back of the socket formed by the ears 14, and the end of the temple-stand prevents movement of the shoe outward.

10. The enlargement or thickening of the arm at 13 affords a firm, broad support for the shoe, resisting any tendency of the latter to be tipped and thereby properly positioning the shoe and maintaining it in such position.

15. The force applied to the shoe to hold it against the side of the slide-bar is regulated by the adjusting screw 12, and by means of the latter the whole device is adjustable to take up wear on the shoe, (which may be 20 made of brass or any other suitable material), and also to provide for slide-bars of different thickness.

Should a shoe become unduly worn it can be readily removed and a new one inserted 25 by loosening the adjusting screw so that the rear end of the arm can be swung out enough to release the shoe.

As the slide-bar is prevented from turning by the means described the wear is reduced 30 to a minimum, and tilting or tipping of the temple-head and roll is prevented, the axis of the roll being maintained in parallelism with the plane of the cloth being woven.

Having fully described my invention, 35 what I claim as new and desire to secure by Letters Patent is:—

1. In a loom-temple, the combination with the stand, and a slide-bar movable longitudinally therein, of a guide-shoe having 40 an extended surface coöperating with the side of the slide-bar, and adjustable means to support and position the shoe in parallelism with the bar irrespective of the adjustment of said means.

45. 2. In a loom-temple, the combination with a slide-bar provided with the temple-

head having a roll, and the temple-stand, of a guide-shoe coöperating with the inner side of the slide-bar, and an adjustable arm mounted on the stand and coöperating with 50 and maintaining the shoe in position to prevent tipping of the slide-bar.

3. In a loom-temple, the combination with the stand, and a slide-bar movable longitudinally therein, of a guide-shoe having 55 an extended surface coöperating with the side of the slide-bar, and provided on its opposite face with a socket, a fulcrum-stud on the stand, an arm mounted on the stud to swing in a lateral path, the rear end of the 60 arm entering the socket in the shoe, to support the latter and maintain it pressed flat against the slide-bar irrespective of the angle of the arm, and an adjusting screw in the outer end of and to regulate the angularity of the arm, said screw bearing against a fixed part of the stand.

4. In a loom-temple, the combination with the stand, and a slide-bar movable longitudinally therein, of a shoe having an 70 extended flat face to bear against the inner side of the slide-bar adjacent the stand, and means adjustably mounted on the latter and frictionally engaging the outer face of the shoe to maintain the latter pressed against 75 the slide-bar and at all times in parallelism therewith.

5. In a loom-temple, in combination, the slide-bar, a stand in which it is longitudinally movable, a laterally movable arm fulcrumed 80 on the stand, means to adjust said arm, and a guide-shoe loosely interposed between the side of the slide-bar and the free end of the arm, to prevent tipping of the slide-bar.

In testimony whereof, I have signed my 85 name to this specification, in the presence of two subscribing witnesses.

CALVIN L. JOY.
